(57) **CLAIM**

We claim the ornamental design for a light source system, as shown and described.

DESCRIPTION

FIG. 1 is a front perspective view from above and one side of the first embodiment of a light source system showing our new design;

FIG. 2 is a front perspective view of the light source system of FIG. 1 from above and the other side thereof;

FIG. 3 is a front perspective view from above and one side of the second embodiment of a light source system having a thumb wheel;

FIG. 4 is a front perspective view of the light source system of FIG. 3 from above and the other side thereof;

FIG. 5 is a rear perspective view of either of the light source systems of FIGS. 1, 2, 3 and 4;

FIG. 6 is a front view of the light source system of FIGS. 1 and 2; and,

FIG. 7 is a front view of the light source system of FIGS. 3 and 4.

The underside of the light source system is not shown and is not a feature of the design.
